UNITED STATES PATENT OFFICE.

VINCENZO MINNELLI, OF PITTSSTON, PENNSYLVANIA.

COMBINED TONE-ARM AND AMPLIFIER.

1,395,053.

Specification of Letters Patent. Patented Oct. 25, 1921.

Application filed July 14, 1920. Serial No. 396,131.

To all whom it may concern:

Be it known that I, VINCENZO MINNELLI, a citizen of the United States, residing at Pittston, in the county of Luzerne and State 5 of Pennsylvania, have invented certain new and useful Improvements in Combined Tone-Arms and Amplifiers; and I do hereby declare the following to be a full, clear, and exact description of the invention, such 10 as will enable others skilled in the art to which it appertains to make and use the same.

This invention has relation to certain new and useful improvements in a combined tone 15 arm and amplifier constructed and arranged for a special tone arm connected with one end of the amplifier mounted on a support taking the place of the usual form of tone arm support while the combined tone arm 20 and amplifier take the place of the usual tone arm and the amplifier or horn.

The invention has for another object the provision of a combined tone arm and amplifier with a special form of tone arm to which 25 is connected the sound reproducer adapted to be turned so as to position the same for playing different types of records such as the records having vertical undulations and those having horizontal undulations for the 30 needle to travel in.

The invention has for a further object the provision of an improved form of combined tone arm and amplifier which will be of simple construction and which may be readily 35 incorporated with a reproducer, a spring motor and a turn table of the form used for graphophones or the like to produce a complete and simplified musical instrument of this character.

40 The invention has for a further object the provision of a simple and efficient form of combined tone arm and amplifier which will be constructed in such a manner that it may be readily assembled and will reduce to the 45 minimum and practically eliminate all metallic sound when the instrument is playing.

The invention has for a still further object, the provision of a novel form of support for the combined tone arm and amplifier and the tone arm connected therewith.

50 The invention has for a still further object, the provision of a novel and simplified form of tone arm having a hinged reproducer carrying portion and a resilient connection between said hinged reproducer car-

rying portion and the adjacent portion of the tone arm which is connected with the delivery duct leading to the tone arm and amplifier so that the tone arm may be readily adjusted upon the delivery duct to raise and lower the reproducer for proper adjustment of the latter over the record to be played.

A still further object of the invention resides in the provision of a combined tone arm and amplifier in which the amplifier will be of substantially elliptical form or the form of a double pyramid and connected with the delivery duct at the apex of one 70 solid pyramid while the side and upper faces of the remaining pyramid are provided with a series of gradually decreasing apertures having a series of perforations and preferably in the form of stars and through which 75 sound waves may escape, the pyramids being hollow and connected at their spaced portions, a central connecting rod being extended through the pyramids to hold them together upon the central connecting rings 80 carried by the support.

With the foregoing and other objects in view as will appear as the description proceeds, the invention consists in the novel construction, combination and arrangement of 85 coöperating elements as hereinafter more specifically set forth, claimed and shown in the accompanying drawings.

With the foregoing and other objects in view as will appear as the description proceeds, the invention consists in the novel construction, combination and arrangement of 90 coöperating elements as hereinafter more specifically set forth, claimed and shown in the accompanying drawings.

In the accompanying drawings forming a part of the present application and in which similar reference characters represent corresponding parts throughout the several views,

Figure 1 represents a plan view of a machine constructed in accordance with this invention.

Fig. 2 is a side elevation of the combined tone arm and amplifier and the mounting therefor together with the tone arm sound 105 reproducer and delivery duct.

Fig. 3 is a longitudinal section on the plane of line 3—3 of Fig. 1.

Fig. 4 is a longitudinal section on the plane of line 4—4 of Fig. 1.

Fig. 5 is a transverse section on the plane 110 of line 5—5 of Fig. 1.

Fig. 6 is a fragmentary detail plan showing the reproducer turned for playing a record having transverse undulations in its grooves.

5 Referring more in detail to the drawings in which similar reference characters designate corresponding parts throughout the several views, 1 indicates the top, 2 the turn table and 3 the supporting base for the combined tone arm and amplifier support of a graphophone or the like and upon the turn table 2 of which is adapted to be positioned in the usual manner a record 4 to be played. The supporting base 3 is located near one 15 rear corner of the top 1 and raised therefrom, as shown in the drawings. The supporting base has a central opening 5 to receive the depending pin 6 carried in the post 7 and loosely mounted therein in such a manner as to prevent the pin 6 from dropping out the post 7. This post 7 has a cup 7' formed around its lower edge and adapted to ride upon the supporting base 3. This post 7 has a transversely concaved and forwardly and downwardly inclined recess 8 in its upper end. A lower horizontal bar 9 is extended forwardly from one face of the post 6 and has a short upstanding hollow post 10 formed on its forward extremity. 25 This post 10 also serves as part of the delivery duct which includes an arm 11 extended laterally from the side of the post. The posts 6 and 10 are braced by the inclined brace bar 12 secured at their upper ends to 30 the posts 6 and 10 respectively, while their lower ends are spaced apart and connected with the arm 9. The post 10 also has a transversely curved and rearwardly and downwardly inclined pocket 13 formed in its upper end.

A central ring 14 has a flat lower portion 15 which is positioned transversely across the center of the arm 9 and is secured thereon by suitable securing members 16 passed 45 through the offset ends of the strap 17 extended beneath the arm 9, as shown in the drawings.

The forward hollow section 18 of the combined amplifier is in the form of a pyramid 50 of octagonal form in cross section and is of such size that its large end is adapted to fit over the flange 19 carried on the forward face of the ring 14 and of octagonal form on its outer or peripheral face. The section 55 18 has an opening 20 in its lower side face which registers with the open upper end of the hollow post 10 when the section 18 is placed in position. A gear section 20 is also in the form of a pyramid of octagonal form 60 in cross section and adapted to engage a flange 22 formed on the rear side face of the ring 14 and having its outer or peripheral edge constructed of octagonal form so as to receive the large end of the rear section 20 65 of the amplifier. This section 20 also has a

plurality of sound wave escape openings arranged on its upper and side faces and preferably graduated in size according to the width of the side and upper sections. These openings 21 are also preferably of the form 70 of stars but may be of any other shape, if desired. The connecting rod 23 extends longitudinally through the amplifier and has nuts 24 or the like threaded upon its opposite ends and bearing against the small ends 75 or apexes of the pyramid forming the ends 18 and 20 of the amplifier. It will therefore be seen that the sections of the amplifier will be securely held together in proper position upon the support provided therefor, 80 but may be readily disconnected, if required.

The angular main section or lower section 25 of the tone arm has one end or one angle engaged in the end of the arm 11 of the delivery duct and adapted to be turned therein 85 for a limited distance, a suitable set screw or guiding pin 26 being carried by the delivery duct 11 to prevent withdrawal of the section 25 of the tone arm and at the same time permit limited movement thereof for proper 90 adjustment of the sound reproducer 27 which is of conventional form and mounted for a limited rotation in either direction on the depending annular portion 28 of the upper hinged section 29 of the tone arm, a 95 suitable pin 30 being carried by this end 28 and extended through a slot 31 carried by the sound reproducer 27. This section 29 of the tone arm also includes a downwardly extended annular portion 33 which is connected 100 by a suitable hinge 34 with the first mentioned section 25 of the tone arm. A suitable spring 35 is also employed to connect the sections 25 and 29 of the tone arm and resiliently retain the section 29 in normal 105 position but permit ready movement thereof on the hinge 34 during the playing of a record, as will be readily understood by those familiar with this art. It is also to be understood that the section 25 of the tone arm 110 does not rotate freely on the delivery duct 11 but will remain in any adjusted position, owing to the frictional engagement of the two parts of the device.

From the foregoing description taken in 115 connection with the accompanying drawings forming a part of the present application, it will be seen that this tone arm and amplifier, owing to the peculiar construction thereof and arrangement of the openings 21 will result 120 in a clear reproduction of the tone recorded on the record being played with all metallic sound reduced to the minimum. Furthermore this combined tone arm and amplifier may be readily constructed of wood 125 or a similar material and assembled on the mounting provided therefor.

While the preferred embodiment of the invention has been shown and described, it will be understood that minor changes in 130

the details of construction and arrangement of parts may be resorted to within the scope of what is claimed without departing from the spirit of the invention.

5 What is claimed is:—

1. In a graphophone structure, an amplifier including an elongated body, a supporting member for said amplifier including a turn post, a supporting base, means for mounting said turn post on the supporting base, a horizontal arm extended from said turn post and having an upstanding forward hollow end, a sleeve extended from said hollow upstanding end and combining therewith to form a sound wave duct to support a reproducer carrying tone arm, angular rest arms extended from the central of said horizontal arm to the turn post and the upstanding end of said horizontal arm, 10 said elongated body of the amplifier resting upon said angular arm and the upper end of said turn post and the upstanding end of said horizontal arm, said amplifier having a sound wave entrance opening communicating with said duct, said amplifier having sound wave escape openings spaced from the sound wave entrance opening, and means for securing said amplifier upon said support.
2. In a graphophone structure, a supporting member including a turn post, an arm extended from said turn post, a hollow member mounted on said arm, an amplifier mounted on said support and having communication with said hollow member, said amplifier having sound wave openings spaced from said hollow member, a side extension carried by said hollow member and forming therewith a sound wave duct,

and a reproducer carrying tone arm adjustably mounted on said side arm of the sound wave duct.

3. An amplifier comprising hollow body sections having open ends, hollow means to join said sections at the open ends, means to support said amplifier for swinging movement relative to a phonograph record, said amplifier having an entrance opening for connection with a reproducer carrying tone arm, said amplifier being provided with sound escape openings at a distance from said entrance opening, and means to secure the sections and hollow means together.

4. An amplifier having hollow body sections wider at one end than at the other, and connecting means for said sections to secure said wider ends in substantial registration.

5. An amplifier having hollow body sections, and connecting means for said sections to urge them toward each other.

6. In an amplifier, a movable bracket, spaced posts on said brackets, an arm bridging the posts, an amplifier means resting on the posts, and means to secure the amplifier means to the arm.

7. In an amplifier, a movable bracket having spaced posts and an arm joining the post, amplifier means resting on the post and being widest intermediate its ends, and means associated with the arm to secure said widest portion thereto.

In testimony whereof I affix my signature in presence of two witnesses.

VINCENZO MINNELLI.
